UNITED STATES PATENT OFFICE.

UNO L. SUNDELAD, OF NEW HAVEN, CONNECTICUT.

SELF-WINDING ELECTRIC CLOCK.

1,143,664.

Specification of Letters Patent. Patented June 22, 1915.

Application filed April 5, 1915. Serial No. 19,174.

To all whom it may concern:

Be it known that I, UNO L. SUNDELAD, a citizen of the United States, residing at New Haven, in the county of New Haven and State of Connecticut, have invented a new and useful Improvement in Self-Winding Electric Clocks; and I do hereby declare the following, when taken in connection with the accompanying drawings and the characters of reference marked thereon, to be a full, clear, and exact description of the same and which said drawings constitute part of this application, and represent, in—

Figure 1 a front view of a self-winding electric clock constructed in accordance with my invention. Fig. 2 a view in horizontal section showing a plan view of the movement and motor. Fig. 3 a sectional view on the line *a*—*b* of Fig. 2, enlarged. Fig. 4 a broken sectional view on the line *c*—*d* of Fig. 3. Fig. 5 a similar view on the line *e*—*f* of Fig. 3. Fig. 6 a rear view of the spring barrel with its slide and dog detached, and shown in the position when the spring is wound. Fig. 7 a similar view showing the position of the parts just before the dog is turned to open the circuit.

This invention relates to an improvement in self-winding electric clocks, and while useful for various purposes, is particularly adapted for use in connection with automobile clocks, the object being a simple arrangement of parts whereby a motor is actuated at intervals to wind the clock, the circuit through the motor being opened and closed by the movement of the usual clock spring, and the invention consists in the construction hereinafter described and particularly recited in the claims.

In carrying out my invention I employ a usual clock mechanism which need not be described other than to refer to the usual spring barrel 2 which contains a spring 3 one end of which is fixed to the barrel 2 and the other end to the main spring arbor 4. This spring barrel is formed with an annular gear 5 meshing with a pinion 6 on the winding shaft 7 which in turn carries a gear wheel 8 meshing with a pinion 9 on the shaft 10 of an ordinary electric motor which will not be described other than to say that one side is connected with a binding post 11 with which one wire from the battery, not shown, is attached. The other side of the motor is connected by a wire 12 with a post 13 mounted in a bridge 14 and insulated therefrom.

The bridge also carries a contact disk 34 with which the post is connected, for the purpose as will hereinafter appear. A binding post 15 for the second wire of the battery is connected with the case 16 and through the case is grounded with the clock movement. Mounted on the rear face of the spring barrel is a slide 17 guided for movement by a screw 18 passing through a clearance slot 19. This slide carries an inwardly projecting pin 20 which extends through a clearance slot 21 in the barrel and enters between the outer convolutions of the spring 3. Also pivotally mounted on the rear face of the barrel above the slide is a dog 22 carrying a contact pin 23 which extends rearward in the plane of the contact disk 34. This dog has a tail 24 extending into line with a shoulder 25 on the slide 17 and so as to be engaged thereby when the slide moves in one direction. Carried by the slide is a tripper 26 mounted on a spring 27, and this tripper is in line with the tail 24 and also in line with a cam 28 on the slide 17. The tripper is also adapted to engage with a notch or slot 32 formed in the spring barrel. The dog is also provided with two notches 29 and 30 adapted to be engaged by a spring detent 31.

Assuming the clock to be wound as shown in Figs. 4, 5 and 6 of the drawings, the spring pin 20 is drawn toward the center of the barrel by the contraction of the convolutions of the spring. At this time the detent 31 engages with the notch 30 as shown in Fig. 6 of the drawings. Now as the spring unwinds the spring pin 20 is carried toward the outer wall of the spring barrel, and when the spring is unwound or nearly so, as shown in Fig. 7, the shoulder 25 strikes the tail 24 of the dog 22 and moves it to one side and until the detent 31 engages with the notch 29. In this movement of the slide the tripper 26 is carried with it until it engages with the notch 32 which then holds the slide in its so called retired position. By this movement of the dog the contact pin 23 has been turned into engagement with the contact disk 34 and hence the circuit through the motor is closed, and as soon as the circuit is closed the motor operates to wind the spring through the winding shaft 7. In winding the spring pin 20 is gradually drawn toward the center of the barrel and in this movement toward the center and at the time the spring is nearly

wound, the cam 28 engages with the tripper 26 and lifts it out of its notch 32 allowing the tripper under the action of its spring 27 to snap forward, striking the tail 24 of 5 the dog 22 and throwing the contact pin 23 out of engagement with the contact disk 34, thus opening the circuit and stopping the motor.

It will thus be seen that simple means are 10 provided so that as soon as the spring is nearly run down the circuit through the motor will be closed, and the spring re-wound, and as soon as the spring is wound to the desired point the circuit will be 15 opened.

I claim:—

1. A self-winding electric clock, the combination with a clock movement including a 20 spring barrel, of an electric motor, connection between the motor and the spring barrel, a contact disk insulated from the clock movement and connected with one side of the motor, a slide mounted on said spring barrel and carrying a spring pin extending 25 into the convolutions of the spring, a dog also mounted on the spring barrel and carrying a contact pin extending into the plane of the contact disk, and means moving with the slide for turning said dog.
2. A self-winding electric clock, the combination with a clock movement including a 30 spring barrel, of an electric motor, connection between the motor and the spring bar-

rel, a contact disk insulated from the clock movement and connected with one side of the motor, a slide mounted on said spring barrel and carrying a spring pin extending into the convolutions of the spring, said slide formed with a shoulder and with a cam, a dog pivotally connected with said 35 spring barrel and having a tail extending between the said shoulder and cam, a spring tripper carried by the slide and extending into the path of the tail of the dog, said dog carrying a contact pin extending into 40 the path of the contact disk.

3. A self-winding electric clock, the combination with a clock movement including a 45 spring barrel, of an electric motor, connection between the motor and the spring barrel, a contact disk insulated from the movement and connected with one side of the motor, a slide mounted on said spring barrel, said slide formed with a shoulder and with a cam, a dog mounted on said spring 50 barrel and having a tail extending between the shoulder and cam, said dog carrying a contact pin extending into the plane of the said contact disk, a spring detent for said dog, a tripper carried by said slide and 55 adapted to engage with said spring barrel when moved in one direction and adapted to engage with the tail of the dog when lifted by said cam out of engagement with the barrel.

UNO L. SUNDBLAD.
